Primary Examiner — Karen E Eldridge Powers(74) *Attorney, Agent, or Firm* — Dunlap Bennett & Ludwig PLLC; Brendan E. Squire(57) **CLAIM**

The ornamental design for a handle for interchangeable painting tool heads, as shown and described.

DESCRIPTION

FIG. 1 is a top front perspective view of a handle for interchangeable painting tool heads showing my new design;

FIG. 2 is a top plan view thereof;

FIG. 3 is a bottom plan view thereof;

FIG. 4 is a front elevation view thereof, with the rear elevation view being a mirror image thereof;

FIG. 5 is a right elevation view thereof;

FIG. 6 is a left elevation view thereof; and,

FIG. 7 is an exploded view thereof.

The broken lines shown in the drawings illustrate portions of the handle that form no part of the claimed design.
